(57) **CLAIM**

The ornamental design for a combined baseball tee and
holder, as shown and described.

DESCRIPTION

FIG. 1 is a top perspective view of the combined baseball tee
and holder according to the invention;

FIG. 2 is a top plan view of the combined baseball tee and
holder of FIG. 1;

FIG. 3 is a bottom plan view of the combined baseball tee
and holder of FIG. 1;

FIG. 4 is a front elevational view of the combined baseball
tee and holder of FIG. 1; and,

FIG. 5 is a rear elevational view of the combined baseball tee
and holder of FIG. 1.
